(57) **ABSTRACT**

A new Verbena plant particularly distinguished by round growth habit; good branching; and bicolour flower color with the upper two petals are purple, while the lower three petals are purple-violet, is disclosed.

1 Drawing Sheet

1

Genus and species: *Verbena x hybrida*.

Varietal denomination: 'KLEVP23124'.

BACKGROUND OF THE NEW PLANT

The present invention comprises a new and distinct variety of Verbena, botanically known as *Verbena x hybrida*, and hereinafter referred to by the variety name 'KLEVP23124'. 'KLEVP23124' originated from a cross-pollination conducted in October 2019 in Cobbitty, New South Wales, Australia between the proprietary female Verbena variety '17.7144' (unpatented), and the commercial male 'KLEVP20052' (U.S. Plant Pat. No. 33,856).

The seeds from the cross were sown and plants were grown for evaluation, where an individual plant designated 'KLEVP23124' was selected from the group of plants in Cobbitty, New South Wales, Australia in October 2019.

In October 2019, 'KLEVP23124' was first vegetatively propagated by vegetative cuttings in Cobbitty, New South Wales, Australia. 'KLEVP23124' was found to reproduce true to type in successive generations of asexual propagation via vegetative cuttings.

SUMMARY

The following are the most outstanding and distinguishing characteristics of this new variety when grown under normal horticultural practices in Cobbitty, New South Wales, Australia.

1. Round growth habit;
2. Good branching; and
3. Bicolour flower color with the upper two petals that are purple, while the lower three petals are purple-violet.

DESCRIPTION OF THE PHOTOGRAPH

This new Verbena plant is illustrated by the accompanying photograph which shows the plant's overall plant habit including form, buds, foliage, and flowers. The photograph

2

is of a plant approximately 12-weeks-old grown indoors in Stuttgart, Germany in May 2022. The colors shown are as true as can be reasonably obtained by conventional photographic procedures.

DESCRIPTION OF THE NEW VARIETY

The following detailed descriptions set forth the distinctive characteristics of 'KLEVP23124'. The data which define these characteristics were collected from asexual reproductions carried out in Cobbitty, New South Wales, Australia. Data was collected on three-month-old plants grown in 2020. Color references are to The R.H.S. Colour Chart of The Royal Horticultural Society of London (R.H.S.), 5th edition (2007).

Classification:

Family.—Verbenaceae.

Botanical.—*Verbena x hybrida*.

Common.—Verbena.

Designation.—'KLEVP23124'.

Parentage:

Female parent.—'17.7144' (unpatented).

Male parent.—'KLEVP20052' (U.S. Plant Pat. No. 33,856).

Plant:

Growth and branching habit.—Upright with a compact and round shape.

Height (from top of soil).—22.6 cm.

Width (horizontal plant diameter).—33.0 cm.

Time to produce a finished flowering plant.—Approximately 8 weeks.

Time to initiate and develop roots.—2 weeks.

Root description.—RHS 155B (White), fine fibrous roots.

Stems:

Number of branches per plant.—More than 25.

Growth habit.—Upright.

Length.—20.0 cm.

Diameter.—0.26 cm.	5	Sepals:
Internode length.—2.1 cm.		Shape.—Lanceolate.
Color.—RHS 139D (Green).		Apex.—Acute.
Anthocyanin.—Absent.		Base.—Fused.
Texture and appearance.—Pubescent.		Margin.—Entire.
Leaves:	10	Length.—1.3 cm.
Arrangement.—Opposite.		Diameter.—0.2 cm.
Immature and mature leaf.—Color: Upper surface: RHS 141A (Green). Lower surface: RHS 141C (Green).	10	Color.—RHS 141C.
Length.—4.1 cm.		Texture.—Upper surface: Hairy, dull. Lower surface: Hairy, dull.
Width.—2.0 cm.		Reproductive organs:
Shape.—Lanceolate.		Stamens.—Present.
Apex.—Acute.		Quantity.—4.
Base.—Obtuse.	15	Color.—RHS 139D.
Margin.—Crenate.		Filament length.—0.3 cm.
Texture.—Upper surface: Leathery. Lower surface: Rugose.		Filament diameter.—0.1 cm.
Venation type.—Pinnate.		Anther.—Shape: Elliptic. Color: RHS 141D. Length: 0.15 cm. Diameter: 0.1 cm.
Venation color.—Upper surface: RHS 141D (Green). Lower surface: RHS 141D (Green).	20	Pollen amount.—Sparse.
Petioles.—Length: 0.3 cm. Diameter: 0.1 cm. Color: RHS 141D (Green). Texture: Leathery.		Pistils.—Number: 1. Length: 1.6 cm. Diameter: 0.1 cm. Stigma: Color: RHS 141D. Appearance: Ovate. Length: 0.1 cm. Diameter: 0.1 cm. Style: Color: RHS 141D. Length: 1.4 cm. Diameter: 0.1 cm. Appearance: Long.
Flower buds:	25	Fruit and seed set: To date, fruit and seed development have not been observed on plants
Shape.—Tall, cylindrical.		Disease and pest/insect resistance: Plants of 'KLEVP23124' have been observed to tolerate powdery mildew (<i>Podosphaera xanthii</i>).
Length.—1.5 cm.		COMPARISON WITH PARENTAL LINES AND KNOWN VARIETY
Diameter.—0.3 cm.		'KLEVP23124' is distinguished from its parents as described in Table 1.
Color (at tight bud).—RHS 68A.		
Inflorescence:	30	
Blooming habit (flowering season).—Continuously.		
Lastingness of individual blooms on the plant.—About a week.		
Fragrance.—Absent.		
Inflorescence type.—Umbel.		
Length of inflorescence.—4.6 cm.	35	
Diameter of inflorescence.—4.9 cm.		
Number of florets per inflorescence.—17.		
Peduncle.—Color: RHS 141A (Green). Length: 2.5 cm. Diameter: 0.2 cm.		
Florets:	40	TABLE 1
Length.—1.8 cm.		Comparison with Parental Lines
Diameter.—1.7 cm.		
Texture.—Smooth.		
Form.—Single.		
Color.—Immature: Upper surface: Upper two petals are RHS 78A (Purple) and the lower three petals distally, close to RHS N81A (Purple-violet) and proximally, close to 155D (white). Lower surface: Upper two petals are RHS 75B (Purple) and the lower three petals, distally, close to RHS 76C (Purple) and proximally, close to 155B (white). Mature: Upper surface: Upper two petals are RHS 77A (Purple) and the lower three petals distally, close to RHS N81B (Purple-violet) and proximally, close to 155D (white). Lower surface: Upper two petals are RHS 75A (Purple) and the lower three petals, distally, close to RHS 76C (Purple) and proximally, close to 155B (white).	45	
Corolla tube length.—1.7 cm.	50	
Corolla tube color.—RHS 157B.	60	
Petals.—Length of lobe: 1.8 cm. Diameter of lobe: 0.8 cm. Lobe shape: Obtuse. Apex: Emarginate. Base: Fused. Margin: Entire. Texture: Upper surface: Glossy, satiny. Lower surface: Glossy, satiny.		
Pedicels.—Not visible.	65	
I claim:		
1. A new and distinct variety of Verbena plant designated 'KLEVP23124' as illustrated and described herein.		

KNOWN VARIETY

‘KLEVP23124’ is distinguished from its parents as described in Table 1.

TABLE 1

Comparison with Parental Lines			
Characteristic		Female parent	Male parent
Flower colour	'KLEVP23124'	'1707144'	'KLEVP20052'

‘KLEVP23124’ is most similar to the commercial Verbena variety ‘KLEVP15616’ (U.S. Plant Pat. No. 28,320).
 50 Differences between the varieties are described in Table 2.

TABLE 2

Comparison with Similar Variety		
Characteristic	‘KLEVP23124’	‘KLEVP15616’
Growth habit	Round	Upright
Branching ability	Better branching than ‘KLEVP15616’	Less branching than KLEVP23124
Flower colour	Bicolour	Solid color with eyes

I claim:

1. A new and distinct variety of *Verbena* plant designated 'KLEVP23124' as illustrated and described herein.
